UNITED STATES PATENT OFFICE.

CHARLES H. TOWNSEND, OF YONKERS, NEW YORK.

VALVE FOR FIRE-EXTINGUISHING SYSTEMS.

1,299,065.

Specification of Letters Patent. Patented Apr. 1, 1919.

Application filed May 6, 1918. Serial No. 232,784.

To all whom it may concern:

Be it known that I, CHARLES H. TOWNSEND, a citizen of the United States, and a resident of the city of Yonkers, county of 5 Westchester, State of New York, have invented a certain new and useful Improvement 10 in Valves for Fire-Extinguishing Systems, of which the following is a specification.

10 My invention relates to a valve adapted for use in connection with fire extinguishing systems, and particularly to that type or character of valve which is automatically opened by the pressure of the water or a 15 reduction of air pressure at the proper time, and the object of this invention is to provide a device of this kind which will be simple in construction and which will be absolutely positive in operation.

20 A further object of this invention is to provide a valve of the above mentioned type which will have its parts so arranged that they are at all times convenient and accessible for regulation and adjustment.

25 These and other objects which may hereinafter appear are accomplished by my invention, a more particular description of which will be hereinafter set forth.

Reference is to be had to the accompanying 30 drawings forming a part hereof, in which,

Figure 1 is a vertical sectional elevation of my improved valve mechanism,

Fig. 2 is a vertical sectional elevation of 35 the structure shown in Fig. 1, taken at right angles thereto, and,

Fig. 3 is a sectional view on the line 3-3 of Fig. 2, looking in the direction of the arrows.

40 Throughout the various views of the drawings, similar reference characters designate similar parts.

In the preferred embodiment of my invention as disclosed in the accompanying 45 drawings, 1 indicates the valve casing which forms a chamber within it, and which is provided at its lower end with the water inlet pipe or opening 2, and at its upper end with the outlet opening 3, through which 50 the water passes to the fire extinguishing system, after being admitted by the valve mechanism, to be described. The upper end of the inlet opening is provided with a suitable valve seat 35 to afford a water tight fit 55 between it and the valve head. This inlet

pipe 2 is also provided with an opening 36 for a draw off valve and pipe for emptying the sprinkler system. It is also adapted for use in determining the vigor of the water supply.

Extending transversely across the interior of the casing 1 is a shaft 4, and this shaft 4 is adapted to rotate about its longitudinal axis in bearings 5 and 6, secured in the walls of the casing 1. The bearing 5 is provided 60 with a recess 7 into which the end of the shaft 4 extends, and within the recess 7 is a coil spring 8 which bears against the end of the shaft 4. Adjacent its other end, the shaft 4 is provided with a conical head 9, 70 and this head 9 fits a complementary shaped opening in the bearing 6 in which the shaft is mounted. It will thus be apparent that the pressure of the spring 8 tends to keep the head 9 tight enough in its opening in 75 the bearing 6 to prevent water, which fills the casing 1, from entering into the chamber 10 containing a valve weight hereinafter referred to.

The valve head or clapper 11 is secured to 80 the shaft 4 by means of an arm 12 keyed on said shaft as at 13. The valve head or clapper 11 is provided at its marginal edge with a rubber ring 34 which affords a tight fit between the valve head and its support when 85 in its lowered position.

It will thus be seen that the pressure of the water on the lower face of the valve head or clapper 11 in a manner hereinafter described 90 will cause the same to pivot upwardly and thus rotate the shaft 4. The means for aiding the valve to assume such upward pivoting movement and to hold the valve open until it is manually closed will now be described.

One end of the shaft 4 extends into the chamber 10, which forms an extension of the casing 1, and within the chamber 10 on the shaft 4 is fixed a segmental gear 14. This segmental gear 14 meshes with a segmental 100 gear 15, loosely mounted on a stud shaft 16 threaded into the wall of the chamber 10 as at 17. The gear 15 is held loosely on the shaft 16 by means of the washer 18 and nut 19.

The segmental gear 15 is provided with an integrally formed weight 20 which extends and moves within the chamber 10. It will be seen that when the valve head or clapper 11 is in closed position over the inlet open- 110

ing 2, the weight 20 is in its upright position, and when the valve head or clapper 11 is swung open or away from the inlet opening, the weight is in its lowered position.

5 When the weight 20 is in its upright position with the valve closed, it is not exactly vertical, but leans at a slight angle to the left, as viewed in the drawings, so that its weight aids in holding down the valve head

10 upon its seat.

The extreme end of the shaft 4 projects outside of the chamber 10, and is preferably square or shaped to fit a suitable tool. After the valve has opened, it is merely necessary 15 to lower the same to its seat by removing the cap 22, which covers the end 21 of the shaft, and engaging the end of said shaft with a suitable tool to oscillate the shaft and close the valve head or clapper 11 down upon the inlet opening 2, and thus correspondingly bring the weight 20 to its upright position.

Situated around the inlet opening 2 is a drain chamber 23. This chamber is provided with an opening 24, through which 25 water is adapted to flow when the valve head 11 is raised, to cause an electric alarm to notify a person in charge of the premises.

There are times, however, when the valve head 11 does not afford a perfect water tight fit upon the end of the inlet pipe 3, and consequently slight drippings enter the chamber 23. At the deepest point in said chamber, which is adjacent the shaft 4, I provide a drain outlet opening 25, and this opening is provided with a valve seat 26 adapted to receive a valve 27. This valve 30 is in the nature of a weight and is provided with an ear 28 to which is secured a lazy tongs 29, the upper joint of the lazy 35 tongs being secured on a pin 30 extending from the wall of the drain chamber. The lazy tongs are provided with projecting ends 31 so that the head or clapper 11 on its downward movement presses on these 40 ends 31 and causes the valve 21 to be drawn up and off its seat 26.

From the foregoing the operation of my improved valve will be readily comprehended.

45 The valve plate 11 is placed in its closed position, or the position shown in Fig. 1, and the interior of the casing 1 is filled, or primed with water through the opening 37 in which a valve is mounted up to a point just below this opening 37. Air is then 50 pumped into the sprinkler system and compressed by an air compressor which works through the opening 38 in the casing 1. The air pressure thus produced on the priming water which rests on the upper or top side of the valve head 11 must be sufficient 55 to hold the valve closed against the water pressure in the supply or inlet pipe 2 beneath the valve head. If the valve seats

properly no leakage water will be observed 65 to flow through the drain opening 25 and the valve is ready for operation in case of fire.

Should a fire occur, the opening of any 70 sprinkler head in the system allows the escape of the air under pressure and thus the pressure of the air on the surface of the priming water within the casing 1 is thus reduced. The upward pressure of the water in the inlet pipe beneath the valve 75 head 11 causes the lifting of this valve head, the chamber 23 thus fills with the result that the entire force of the water exerted over the full area of the under side of the valve head 11, aided by the weight 20, swings 80 it upward to its open position, as shown in dotted lines in Fig. 1 and leaves a straight unobstructed passage for the water to pass through to the sprinkler system.

As the valve head or clapper 11 swings 85 upwardly away from its seat to the position shown in dotted lines in Fig. 1, it consequently releases its pressure on the ends 31 of the lazy tongs 29 and the valve 27 by reason of its own weight, drops into position 90 on its seat 26, thereby closing the drain opening 25. Water thus passes through the alarm opening 24 in the chamber 23 to cause the electric alarm hereinbefore referred to.

The weight 20 holds the valve 11 in its 95 open position, and after the fire has been extinguished, and it is desired to close the valve, this is done by merely removing the cap 22 and rotating the shaft 4 by its end 21 as heretofore referred to. The casing 1 100 is provided with a suitable cover or plate 32, and the chamber 10 with a plate 33, allowing an inspection of the parts whenever desired.

It is to be noted that the valve plate 11 105 when in its closed position on its seat is placed at an inclined position, or at an angle to the horizontal. By this arrangement a rapid opening of the valve is produced as the distance of travel of pivoting movement 110 of the valve when opening is thus shortened.

From the foregoing, it is obvious that my invention is not limited to the exact embodiment herein shown, but is broad enough to cover all structures coming within the scope 115 of the annexed claims.

What I claim is:

1. A device of the class described comprising a casing, an opening leading into said casing, a valve adapted to cover said 120 opening, a pivot for said valve, a gear on said pivot, a pivoted weight and a gear on said weight engaging the valve pivot gear.

2. A device of the class described, comprising a casing, an opening in the same, 125 a valve for said opening, an oscillating shaft, means connecting said shaft with the valve, a segmental gear on said shaft, a

weight and a segmental gear on said weight engaging the segmental gear on said shaft.

3. A device of the class described, having a casing, said casing being provided with an inlet opening, a valve adapted to cover said opening, a rotatable shaft connected to said valve, a spring bearing on one end of said shaft, a conical head adjacent the other end of said shaft, a bearing supporting said end, said bearing having a complementary seat for said head, a segmental gear on said shaft, and a weight having a segmental gear adapted to engage the segmental gear on said shaft.

4. A device of the class described, comprising a casing having an inlet opening, a valve adapted to be swung to and from said opening, said casing having a drain opening below the valve, a valve for said drain opening, a lazy tongs for holding said valve, means for causing the inlet valve to engage said lazy tongs and hold the drain valve elevated above its opening, and means

for causing the drain valve to close the drain opening when the inlet valve is elevated. 25

5. A device of the class described, comprising a casing having an inlet opening, a valve adapted to cover said opening and adapted to be swung to and from the same, said casing having a drain opening, a valve 30 for said drain opening, a lazy tongs for supporting said drain valve above the drain opening, means for causing said valve to be held open while the inlet valve is closed and closed while the inlet valve is open. 35

6. A device of the class described, comprising a casing, said casing having an inlet opening, an inclined seat on said inlet opening, a pivoted valve adapted to rest on said seat, a gear on the valve pivot, and a pivoted weight having a gear engaging the valve pivot gear. 40

Signed at the city, county and State of New York, this 19th day of April, 1918.

CHARLES H. TOWNSEND.
